US0D1089530S

(12) **United States Design Patent** (10) **Patent No.:** **US D1,089,530 S**
(45) **Date of Patent:** **** Aug. 19, 2025**

(54) **SPRINKLER**

(71) Applicant: **Tyco Fire Products LP**, Cranston, RI (US)

(72) Inventor: **Jeremy Cogswell**, Johnston, RI (US)

(73) Assignee: **Tyco Fire Products LP**, Cranston, RI (US)

(**) Term: **15 Years**

(21) Appl. No.: **29/943,546**

(22) Filed: **May 22, 2024**

(57) **CLAIM**

The ornamental design for a sprinkler as shown and described.

DESCRIPTION

FIG. 1 is a front perspective view from above of an embodiment of the claimed sprinkler;

FIG. 2 is a rear perspective view from below of the claimed design of FIG. 1;

FIG. 3 is a front side view of the claimed design of FIG. 1; FIG. 4 is a right side view of the claimed design of FIG. 1; FIG. 5 is a left side view of the claimed design of FIG. 1; FIG. 6 is a rear side view of the claimed design of FIG. 1; FIG. 7 is a top side view of the claimed design of FIG. 1; and,

FIG. 8 is a bottom side view of the claimed design of FIG. 1.

Any portion of the article depicted in broken lines forms no part of the claimed design.

1 Claim, 7 Drawing Sheets
